United States Patent Office.

CHARLES KENISTON, OF SOMERVILLE, MASSACHUSETTS.

Letters Patent No. 98,068, dated December 21, 1869.

IMPROVEMENT IN LEATHER-SPLITTING MACHINES.

The Schedule referred to in these Letters Patent and making part of the same.

To all whom it may concern:

Be it known that I, CHARLES KENISTON, of Somerville, in the county of Middlesex, and State of Massachusetts, have invented an Improved Leather-Splitting Machine; and I do hereby declare the following, taken in connection with the drawings which accompany and form part of this specification, is a description of my invention, sufficient to enable those skilled in the art to practise it.

My invention relates to an arrangement or organization of mechanism for splitting leather.

In ordinary leather-splitting, (as is well known to persons skilled in the manufacture of boot and shoe-stock, and other leather stock,) the feed-rolls push the leather straight forward against a stationary splitting-knife edge, (the knife having no movement, and the rolls only rotating,) and, with many thin skins, it is impossible to split accurately with such machines, however sharp may be the cutting-edge.

To remedy this difficulty, machines have been, to a limited extent, made, in which the knife reciprocated, thereby imparting to its cutting-edge a drawing stroke.

Now, although such movement of the knife causes the leather to be cut more readily, it prevents the employment of a knife which is made rigid and unbending, by reason of its firm attachment to a solid bed-piece, and the cutting-edge is apt to spring or buckle.

By my improvement, I employ a rigid stationary knife, fastened to its bed, as in ordinary leather-splitters, and I give to the feed-rolls, in addition to their feed or rotative movement, a reciprocating movement, thereby obtaining all the advantages possessed by a reciprocating knife, without the objections inherent thereto.

My invention consists, therefore, in a leather-splitting machine, having, in combination with a stationary knife or cutter, feed-rolls, which reciprocate the leather as they present it to the cutting-edge of the knife.

The drawings represent a machine embodying the improvement.

A shows the machine in plan.

B is a vertical cross-section of it.

a a denote the standards, supporting a bed-piece, *b*, to the top of which is bolted the knife-cutter *c*, whose cutting-edge *d* projects between the feed-rolls *e f*, as seen at B, the cutter having suitable provision for adjustment of its edge toward or from the rolls.

The journals *g* of the lower feed-roll turn in sliding bearings *h*, forced upward by strong springs *i*, and the journals *k* of the upper roll turn in vertically-sliding bearings *z*, drawn upward by springs *l*, the extent of upward movement of the bearings *k* being adjustably determined by stop-screws *m*, or other suitable devices.

The journals *g* extend beyond their bearings *h*, and the roll is made shorter than the bed, so that the roll can be moved to and fro (in the line of its axis) between the standards.

At the end of one of the journals *g*, a cam-wheel, *n*, is fixed, this wheel having a zigzag cam-groove, *o*, into which projects a pin or roll, *p*, on a stud, *q*, projecting from the adjacent standard, as seen at A, so that as the roll is rotated by a suitable crank, *r*, a short reciprocating movement is imparted to the roll.

The two rolls are geared together by gears *s t*, and one of the gears may be made with flanges embracing the meshing-teeth of the other gear, to effect a similar reciprocating movement of the upper roll, whose journals also slide in their bearings.

The machine thus made, is very strong and enduring, simple in construction, and effective in operation, and the provision for reciprocation of the rolls adds but very little to the cost of the machine over the cost of those in ordinary use, while the improvement not only enables the splitting to be much more easily effected, but causes the leather to be more accurately and evenly split than in other machines.

I claim, a leather-splitting machine, having a stationary knife or cutter, and reciprocating feed-rolls, operating substantially as described.

CHARLES KENISTON.
